UNITED STATES PATENT OFFICE.

SAM KATZ, OF NEW YORK, N. Y.

WAISTBAND FOR TROUSERS.

SPECIFICATION forming part of Letters Patent No. 562,617, dated June 23, 1896.

Application filed April 22, 1896. Serial No. 588,560. (No model.)

To all whom it may concern:

Be it known that I, SAM KATZ, a citizen of the United States, residing at New York, in the county and State of New York, have invented a new and useful Improvement in 5 Waistbands for Trousers, of which the following is a specification.

My present invention relates particularly to waistbands for boys' knee-trousers, and the 10 object of the same is to provide an economically-made band of a single piece of longitudinally-folded fabric in which the elastic strips are not visible and are therefore not objectionable or unsightly.

15 In carrying out my invention the strip of fabric is longitudinally folded with a double fold on the upper edge of the waistband, the parts of this fold being united by a line of sewing, and two parallel fabric portions being 20 formed along one edge of this double fold. The back portion of this strip is folded double upon itself and is united to the other parts near its lower edge, and the front portion is also folded double upon itself and the free 25 edge may be returned at the back of the waistband to form the back lining or it may extend down to form a skirt to the waistband.

In the drawings, Figure 1 represents, by an 30 elevation, the greater portion of my improved waistband. Fig. 2 is a section in larger size at x x of Fig. 1. Fig. 3 is a similar section at y y of Fig. 1. Fig. 4 is a similar section to Fig. 3, but with the parts drawn out and the elastic distended. Fig. 5 is a perspective view 35 in larger size of a piece of the band from the back, as hereinafter more particularly described. Fig. 6 is an elevation representing a slightly-modified form of my improved waistband. Fig. 7 is a section in larger size 40 at x' x' of Fig. 6. Fig. 8 is a similar section at y' y' of Fig. 6, and Fig. 9 is a section similar to Fig. 8 with the parts drawn out and the elastic distended.

In Figs. 1 to 5, inclusive, the fabric forming 45 the waistband is a single piece longitudinally folded with a double fold a along the upper edge and with the front portions b and the back portion c of fabric extending from and along one edge of said double fold. Of these 50 two parts, the portion b extends down and is folded up and down upon itself at the folds 2 and 3, and the same is again folded at 4 and

the fabric returned upward to form the back lining b' , and above the fold 4 at line 5 and at the upper edge of the back lining at line 6 55 the fabric is to be connected by sewing to the waistband A of the trousers.

The portion c extends down from the double fold a and its free edge is divided at two places at the lines z z , Figs. 1 and 5, so as to 60 be folded in one manner at the inflexible portion of the band and in another manner where the elastic strips come. At the inflexible portion, Fig. 2, this portion is folded upon itself at 16, Figs. 2 and 5, and said fold and the free 65 edge come within the back lining b' .

Where there are elastic strips d , as shown in Figs. 3 and 4, the strip c is folded upon itself double at the folds 7 8 with the free edge 9 adjacent to the fold 4 of the portion b , and 70 the elastic strips d come between the portions b c and their respective double folds, as seen in Figs. 3 and 4, there being a waved line of sewing at 10, connecting the thicknesses of fabric together and to the elastic strips, and 75 the line of sewing at 11, that runs the whole length of the band and connects the portions of the fabric near the fold 4 with the elastic strips, excepting the fold 2 in Figs. 2 and 3 and the folds 7 and 8 in Figs. 3 and 4. 80

The back lining b' adjacent to the elastic strips d is longitudinally separated at 12 to allow for stretching the elastic bands, the parts assuming the position shown in Fig. 4, in which operation the doubly-folded portion c is 85 drawn out almost straight, the same being capable of limiting the stretch of the elastic strips, and the doubly-folded portion b is also partially drawn out. It will be noticed from these figures that the line of sewing at 5, connecting the lower edge of the waistband to the trousers, comes behind the folded edge 2, so that said line of sewing is concealed from view, and should the same be made with dark 90 thread like the trousers said line of sewing 95 will not be objectionable, because invisible.

In the modification shown in Figs. 6 to 9, inclusive, the portion b is doubly folded at 2 and 3, as hereinbefore described, and the lower free edge is continued down to form 100 the skirt b^2 , which may be of any desired length, and the portion of c that is doubly folded extends the full length of the band, and a separate piece is employed at e as a

back lining, the same being connected at the waved line of sewing 10 to the waistband, and at the line of sewing 6 to the trousers, there being in this waistband, as in the form 5 before described, doubly-folded portions in both the strips *b* and *c* at the respective sides of the elastic strips, the one being almost drawn taut as the elastic strips are stretched and the other left somewhat slack, as indicated in Fig. 9, the fabric if fully straightened limiting the stretch of the elastic strips, so that the same will not be unduly strained when distended.

I claim as my invention—

1. The waistband for trousers consisting of a longitudinally-folded strip of fabric having a fold at the upper edge and double folds in each of the adjacent portions *b* and *c*, and elastic strips, the folds coming at the respective sides of and inclosing the elastic strips and being drawn out as said strips are stretched or distended, substantially as set forth.

2. The waistband for trousers consisting of a single longitudinally-folded strip of fabric having a fold at *a* along its upper edge and double folds in the respective portion *b c*, and elastic strips between the respective folded portions, the free edge of the portion *b* being again folded at 4 and extending upward to form the back lining and to inclose the double fold of the strip *c*, said back lining being longitudinally separated adjacent to the elastic strips so as to allow the double folds to open when the elastic strips are stretched or distended, substantially as set forth.

3. The waistband for trousers consisting of a double longitudinally-folded strip of fabric

having a double fold *a* on its upper edge and two parts *b c* and elastic strips between them, the portion *b* being folded double upon itself at 2 3 and again at 4, with the free edge extending upward to form the back lining *b'*, and connected to the trousers by lines of sewing at 5 and 6, the portion *c* extending down and having two incisions at *z z*, in its free edge the portions between the ends of the band and said incisions at the inflexible portions of the band being folded at 16, and the other portion between the incisions and adjacent to the flexible elastic strips being folded doubly upon itself at 7 and 8, with the free edge adjacent to the fold 4 and connected by sewing to the fabric portions and to the elastic strips, and the back lining having a longitudinal incision at 12 for permitting the double-folded portions to open out as the elastic strips are stretched or distended, substantially as set forth.

4. A waistband for trousers consisting of a single longitudinally-folded strip of fabric having a double fold *a* on its upper edge and two parts *b c* and elastic strips between the portions *b c*, the portion *b* being folded double upon itself at 2 3 and the portion *c* being folded double upon itself at 7 8, and the lower edges of said portions together with the elastic strips being sewed to the band of the trousers at the line 5 behind the folded edge 2, so that said line of sewing is concealed from view, substantially as set forth.

Signed by me this 15th day of April, 1896.

SAM KATZ.
